UNITED STATES PATENT OFFICE.

ARCH B. GREEN, ROBERT G. REEVE, AND ROSCOE C. BERLIN, OF SAN FRANCISCO, CALIFORNIA.

DESIGN FOR A FRUIT-JUICE DISPENSER.

Application filed December 26, 1928. Serial No. 29,418. Term of patent $3\frac{1}{2}$ years.

To all whom it may concern:

Be it known that we, ARCH B. GREEN, ROBERT G. REEVE, and ROSCOE C. BERLIN, citizens of the United States of America, and residents of the city and county of San Francisco and State of California, have invented a new, original, and ornamental Design for Fruit-Juice Dispenser, of which the following is a specification, reference being had to the accompanying drawing, forming part thereof, and in which the figure is a front perspective view of the fruit-juice dispenser.

We claim:

The ornamental design for a fruit juice dispenser, as shown.

ARCH B. GREEN.
ROBERT G. REEVE.
